UNITED STATES PATENT OFFICE.

WILLIAM BROOKS MURRAY, OF DANVILLE, ILLINOIS, ASSIGNOR TO THE MILLER TRAIN CONTROL CORPORATION, OF STAUNTON, VIRGINIA, A CORPORATION OF VIRGINIA.

TRAIN-CONTROL SYSTEM AND APPARATUS.

1,254,839.

Specification of Letters Patent. Patented Jan. 29, 1918.

Application filed December 27, 1913. Serial No. 809,086.

To all whom it may concern:

Be it known that I, WILLIAM BROOKS MURRAY, a citizen of the United States, residing at Danville, in the county of Vermilion and State of Illinois, have invented certain new and useful Improvements in Train-Control Systems and Apparatus, of which the following is a specification.

This invention relates to improvements in train control systems, adapted for use in connection with locomotives, cars or other rolling stock propelled by steam, electricity, or the like, and has particular reference to mechanically operated and electrically controlled means or instrumentalities for operating train stopping means or signaling means or both.

An important object of this invention is to provide improved mechanically operated and electrically controlled apparatus carried by the locomotive or other vehicle, which is simple and durable in construction, reliable in operation, inexpensive to manufacture and not liable to injury or derangement.

Another object of this invention is to provide means of the above mentioned character embodying a contact member or contact member support which may be freely moved vertically by an obstruction such as a misplaced stone, tie, or pile of cinders along the road bed, without injury to the contact member or contact member support and without effecting the operation of the train stopping or signaling means or both but which will actuate the same as herein-after described when moved or swung laterally by suitable means provided for the purpose under certain track conditions.

A further object of the invention is to provide means of the above mentioned character so constructed that the mechanically operated element or elements embodied therein will be rendered operative and inoperative with respect to operating the train stopping or signaling means or both, in accordance with the track conditions when the locomotive or train is traveling in one direction, and which will be rendered inoperative with respect to operating both the train stopping and signaling means when the locomotive or train is traveling in an opposite direction as when the locomotive or train is backing.

A further object of this invention is to provide simple and reliable fluid pressure

operated means for automatically either cutting off the motive power or applying the brakes or both, at selected points along the right of way when the track conditions are such as to render the stoppage of the locomotive or train necessary to avoid danger of accident and at no other time, except in the case of injury to the apparatus.

A further object of this invention is to provide means for automatically stopping the locomotive, train, or the like, preferably by the reduction of pressure in the train line, upon the destruction of or substantial injury to the contact member or contact member support.

A further object of this invention is to provide an improved track circuit or circuits for use in connection with the mechanically operated and electrically controlled means carried by the locomotive or train.

A further object of this invention is to provide a novel form and arrangement of a ramp or ramps, included in the track circuit, whereby the same are not liable to have their contact faces covered or obstructed by foreign material, such as ashes, snow, ice or the like, and particularly to such an extent that the same may not be readily automatically cleaned by the engagement therewith of the contact members carried by the locomotive or train.

Other objects and advantages of this invention will be apparent during the course of the following description.

In the accompanying drawings forming a part of this specification and in which like numerals are employed to designate like parts throughout the same,

Figure 1 is a diagrammatic view of track circuit or circuits and associated elements, embodying my invention,

Fig. 2 is a transverse sectional view taken through the traffic rails, showing corresponding ends of the ramps in elevation,

Fig. 3 is a side elevation of one set of ramps,

Fig. 4 is a plan view of the same,

Fig. 5 is an enlarged transverse sectional view taken on line 5—5 of Fig. 3,

Fig. 6 is a side elevation of the rear portion of a railway locomotive, showing my apparatus in use thereon,

Fig. 7 is an enlarged edge elevation of mechanically operated and electrically controlled means carried by the locomotive,

Fig. 8 is a plan view of the same, parts being omitted,

Fig. 9 is an enlarged side elevation of the same,

Fig. 10 is a still more enlarged detail section taken on line 10—10 of Fig. 9,

Fig. 11 is a transverse section taken on line 11—11 of Fig. 10,

Fig. 12 is an enlarged detail section 10 through a valve structure included in the invention,

Fig. 13 is a transverse section taken on line 13—13 of Fig. 12,

Fig. 14 is an elevation, in the engine cab, 15 of fluid pressure operated means for cutting off the motive power and applying the brakes, and,

Fig. 15 is a plan view of the fluid pressure operated means for cutting off the 20 motive power.

Attention being called first to Fig. 1, the numerals 20 and 21 designate traffic rails of an ordinary railroad track having traffic in one direction, as indicated by the arrows.

25 These traffic rails are insulated at spaced intervals, as shown at 22, for dividing the track into a plurality of blocks of suitable length. For the sake of clearness I have designated the blocks by reference characters, A, B, C, and D. For the purpose of illustration I have shown the block B at "clear", the block C at "caution", and the block D at "danger" conditions.

Each block is provided with a local track 30 circuit, comprising a source of current 23, preferably arranged near the exit end thereof, as shown. This source of current has one pole thereof connected with the traffic rail 20 of the block by a wire 24, 40 while the opposite pole of the source of current is connected with a wire 25, which in turn is connected with the traffic rail 21 of the block. Arranged preferably near the entrance end of each block is an electro- 45 magnet or electrically operated device 26, having one end of its winding connected with a wire 27, which is in turn connected with the traffic rail 21 of the block. The opposite end of the winding of the electro- 50 magnet 26 is connected with a wire 28, which is in turn connected with the traffic rail 20 of the block. The electro-magnet 26 is included in a relay for controlling the electrical connection between ramps and a 55 source of current, as will be explained.

Arranged in advance of and suitably near the entrance end of each block are ramps 29 and 30, disposed in spaced superposed relation, as clearly shown in Fig. 5. These 60 ramps 29 and 30 are curved outwardly longitudinally in a substantially horizontal plane, as shown. The upper ramp 29 is formed in two ramp-sections 29^a and 29^b, insulated at 20°, while ramp 30 is formed in 65 two ramp-sections 30^a and 30^b, insulated at

20°, as shown. While it has heretofore been generally supposed that a relatively short ramp or ramps could be successfully employed in train control systems more or less analogous to mine, yet I have found by 70 thorough and practical tests that such is not the case. On the contrary, I have found that such ramps or ramp-sections when the ramp is divided, cannot be advantageously employed, when they are materially under 75 50 feet in length. I have found that the best results are obtainable by making each ramp-section 90 feet or over in length; while satisfactory results are obtainable by making them from 75 to 100 feet in length. The 80 ramps 29 and 30 are rigidly connected with and insulated from upstanding supports or brackets 30', retained in fixed positions by any suitable means.

Arranged suitably near the entrance end 85 of each block is a signal or semaphore paddle 32, adapted to assume three positions, to wit, an uppermost position for indicating a clear block, an intermediate position for indicating caution condition, and 90 a lowermost position for indicating danger or stop condition. Any suitable means may be employed to shift or move the semaphore paddle, the same forming no part of my invention, for which reason it is thought unnecessary to show them.

Preferably arranged near the exit end of each block is a source of current 33, having one pole thereof electrically connected with the track rail 21 of the adjacent rear block. The opposite pole of this source of current is connected with a wire 34, the free end of which is electrically connected with both ramp-sections 29^b and 30^b, as shown. Connected with the ramp-section 30^a is a wire 100 35, while a wire 36 is connected with the ramp-section 29^a, as shown. The wires 35 and 36 are connected with transversely aligned stationary contacts 37 and 38 respectively, insulated from each other, as 105 shown. Arranged outwardly of and near the stationary contact 37 is a stationary contact 39, connected with the wire 36 by means of a wire 40, as shown. Arranged near and in co-operative relation to each set 110 of contacts 37, 38, and 39, is a pivoted and vertically swinging contact blade 41, adapted when in its lowermost position to be free from engagement with all of the contacts 37 to 39 inclusive, as clearly shown in connection with block D, adapted to engage with contact 39 alone, when in its intermediate position, as shown in connection with block C, and adapted to disengage contact 39 and simultaneously engage contact 37 and 38, 115 when in its uppermost position, as clearly shown in connection with block B. The contact blade 41 is permanently electrically connected with a wire 25', connected with a stationary contact 27', adapted to be en- 120

125

gaged by an armature 26' of the electro-magnet 26. This armature is electrically connected with one pole of the source of current 33, and is held in electrical engagement with the contact 27', when the electro-magnet is energized, but will break such engagement upon the electro-magnet being de-energized. The contact blade 41 is swung vertically in the same direction with the paddle 32, and for thus purpose the contact blade is provided with a crank 42, extending laterally beyond the pivot of the same, such crank being pivotally connected with an upwardly extending rigid rod 43, having 15 pivotal connection with a crank 44, rigidly connected with and extending laterally beyond the pivot point of the semaphore paddle 32, as shown. It is thus seen that as the semaphore paddle is raised or lowered 20 to the several different positions, the contact blade 41 will assume corresponding positions.

The mechanically operated and electrically controlled means embodied in the invention is shown in Figs. 6 to 10 inclusive, to which attention is now called. The numeral 45 designates a preferably vertically arranged plate or support, which is preferably rigidly attached by any suitable means 30 to the frame of the locomotive, preferably near and in advance of the driving wheels thereof, as clearly illustrated in Fig. 6. As more clearly shown in Figs. 7, 8 and 9, the support 45 is provided near and spaced from 35 its lower end with a pair of laterally extending apertured ears 46, between which is arranged a normally preferably vertically arranged tubular casing 47, carrying trunnions 48, passing through the apertures in the ears 46. It is thus seen that this casing or housing cannot move vertically perceptibly with 40 relation to the apertured ears 46 but it is free to be swung laterally with relation thereto. The upper end of this vertically 45 laterally swinging tubular casing or housing 47 is provided with a substantially T-shaped head 49, including oppositely extending hit-and-miss arms 50 and 51, as shown in Figs. 6 and 9. The function of the T-shaped head 50 will be explained hereinafter.

As more clearly shown in Figs. 6, 7, and 9, the numeral 52 designates a vertically reciprocating bar or element, slidably mounted within the lower portion of the casing or 55 housing 47, as shown. The upward movement of the bar or element 52 is opposed by a suitably stiff compressible coil spring 53, mounted within the upper portion of the tubular casing or housing 47, while its 60 downward movement is positively limited by trunnions 54, carried thereby and operating within elongated slots 55, as shown. Rigidly connected with and preferably formed integral with the lower end of the 65 reciprocating bar or element 52 is a contact

member or contact member support or shoe 56, carrying upon the inner face thereof, laterally reciprocating contacts 57 and 58, arranged in spaced superposed relation, for engagement with the ramps 29 and 30 respectively, as shown. These contacts 57 and 58 are rigidly mounted upon tubular fiber insulating elements 59, mounted to reciprocate within transverse openings 60, as more clearly shown in Fig. 10. These tubular insulating elements are positively limited in their outward movement with respect to the shoe 56 by annular flanges 61, formed thereon, as shown. These annular flanges are arranged within transverse chambers or recesses 62, within which are mounted suitably stiff compressible and expandable coil springs 63, engaging within the tubular elements 59, to force the same outwardly, as shown. The free ends of the chambers 62 are normally closed by a movable plate or door 64, secured in place by means of screws or bolts 65 or the like. I preferably arrange a section of insulation 66 upon the inner face of the shoe 56, between the same and the contacts 57 and 58, to prevent them from having electrical contact with the shoe 56. It is thus seen that the contacts 57 and 58 are laterally movable with respect to the shoe 56 and are thoroughly insulated therefrom.

As more clearly shown in Figs. 7 and 9, the support 47 is apertured near its upper and lower ends to loosely receive transverse horizontal reciprocating bolts 66' and 67', each of which is provided at its opposite ends with enlarged heads 68 and 69, as shown. Arranged between the outer heads 69 and the support 45 are suitably stiff compressible and expandable coil springs 70^a, of the same strength, the same surrounding the bolts 66' and 67', as shown. These coil springs normally serve to hold the bolts 66' and 67' in their outer positions with their outer heads 69 just or almost engaging but 105 slightly spaced from the upper and lower ends of the pivoted casing or housing 47. The function of the bolts 66' and 67' and their springs 70^a is to normally retain the housing or casing 47 in its vertical position, 110 but allowing the same to be moved laterally in either direction, and automatically returning the same to the normal vertical position, upon being released. It is obvious that the lower end of the housing or casing 115 47 and associated elements, will be swung laterally outwardly upon engagement of the contacts 57 and 58 with the ramps 29 and 30, when the engine passes the same.

Arranged inwardly of and near the upper 120 end of the support 45 are preferably horizontally arranged valve structures 70, 71, 71', which are identical, whereby a detail description of one will suffice for both. In Fig. 12, one of these valve structures, is 125

shown, comprising a cylinder 72, provided at its inner end with a pressure supply pipe 73 connected with a fluid pressure supply source, such as the main reservoir. The cylinder 72 is provided at its opposite end with an outlet pipe 74, for a purpose to be described. Arranged within the outer portion of the cylinder 72, upon one side of the pipe 74, is a stationary plate or wall 75, provided 5 with a laterally extending annular flange 76, within which are arranged apertures or ports 77, as shown. The annular flange 76 serves as a seat for a valve 78, normally held seated by a spring 78' and the pressure 10 within the cylinder 72. This valve is connected with a valve rod 79, extending outwardly beyond the cylinder 72 through a stuffing box 80, of any well known or preferred type.

15 Pivottally connected with the outer ends of the valve rods 79 of the valve structures 70 and 71, as shown at 81, are vertically swinging normally horizontal operating rods 82 and 83, as more clearly shown in 20 Figs. 8 and 9. These operating rods pass through transverse openings 84, and are supported in their horizontal positions by the lower walls thereof. The outer ends of the rods 82 and 83 are arranged to coöperate with the arms 50 and 51, as will be explained.

25 The rods or arms 82 and 83 are preferably provided with armatures 86 and 87, respectively, disposed near and below electro-magnets 88 and 89, as shown. These electro-magnets 88 and 89 are preferably vertically arranged and are rigidly attached to the upper end of the support 45, as shown. It is thus seen that when the arms 50 and 30 51 of the T-shaped head 49 are swung inwardly, they will strike the ends of the rods 82 and 83 to move them inwardly, to unseat the valves 79, if the magnets 88 and 89 are deenergized, but when these magnets are 35 energized, said rods 82 and 83 will be raised so that they will clear the arms 50 and 51. The electro-magnet 88 has one end of its winding connected with an insulated wire 57', connected with the contact 57, the opposite end of such winding being grounded to the frame of the engine by an insulated wire 88'. The other magnet 89 has one end of its winding connected with an insulated wire 58', electrically connected with contact 40 58, the opposite end of such winding being grounded to the frame of the engine by a wire 89'. The valve rod 79 of the valve structure 71' has no pivoted extension or rod, but is permanently disposed in the 45 path of travel of the T-shaped head 49, whereby this valve structure is operated upon each lateral movement of the head 49.

50 As more clearly shown in Fig. 6, the outlet pipe 74 of the valve structure 70 passes into the cab of the locomotive and has a T-

coupling 90 connected therein, as shown. Connected with this T-coupling is a pipe 91, leading into the intake end of a cylinder 92, held stationary by any suitable means. The cylinder 92 has a piston 92' mounted to reciprocate therein, which is connected with a piston rod 93, having suitable pivotal connection with an engineer's air brake valve lever 94. When fluid pressure is supplied into the cylinder 92, the piston 92' is moved forwardly and through the medium of the rod 93 moves lever 94 for reducing the pressure in the train line, and applying the brakes. After the supply of pressure is cut off from the cylinder 92, the 55 pressure contained therein may be exhausted to the atmosphere, by manipulation of a valve or pet-cock 93', subsequently to which the lever 94 may be returned to the inactive position. The pipe 74 leads into one end of a throttle lever operating cylinder 95, within which is mounted to reciprocate a piston 96, connected with a piston rod 97, as more clearly shown in Fig. 15. The cylinder 95 is preferably rigidly attached to the rear end of the boiler of the locomotive by means of brackets 98 or the like. The outer end of the piston rod 97 is pivoted, as shown at 99, with a bell-crank lever 100, which is pivoted to a fixed bracket 101, as 60 shown at 102. The outer arm of the bell-crank lever 100 is pivoted, as shown at 103, with a link 104, traversing a throttle lever 105. This link is provided with outwardly extending trunnions or pins 106 and 107, 65 arranged upon the opposite side of and normally slightly spaced from the throttle lever 105, as shown. The link 104 is pivoted at its free end, as shown at 108, with a bell-crank lever 109, connected with the throttle lever 105, as shown at 110. The bell-crank lever 109 is urged in one direction by a suitably stiff retractile coil spring 111, as shown. The bell-crank lever 109 is pivotally connected with a link 112, having suitable connection with a latch rod 113, mounted within guides 114. To the inner end of the latch rod 113 is secured a latch 115, moved into engagement with teeth 116 of a stationary quadrant 117, by means of a suitably stiff 70 compressible and expandible coil spring 118. The latch 115 is also manually operated by a hand grip 119, as shown. Pivotally connected with the throttle lever 105, as shown at 120, is a link 121, having pivotal connection with a throttle valve stem 122. When pressure is supplied to the cylinder 95, the piston 96 thereof moves forwardly, whereby the outer arm of the bell-crank lever 100 is swung inwardly. This movement of the bell-crank lever 100 moves the link 104 inwardly, which at first moves the bell-crank lever 109, to release the latch 115. Upon the further movement of the bell-crank lever 100, outer trunnion 107 engages 75 125

130

the throttle lever 105, and swings the same inwardly, to cut off the supply of steam to the engine cylinders, to stop the locomotive. The fluid pressure means operating the engineer's air brake valve and throttle lever, are so adjusted that the brakes are applied a little in advance of the cutting off of the steam or motive power.

The outlet pipe 74' of the valve structure 10 71, as clearly shown in Fig. 6, extends into the cab and is connected with a whistle or signaling means 123, as shown. The outlet pipe 74² of the valve structure 71' extends 15 into the cab and is connected with a whistle 123', capable of making a different sounding signal from that produced by the whistle 123.

Means are provided to reduce the pressure in the main reservoir and ultimately 20 in the train line and apply the brake to stop the locomotive should the bar or element 52 break off or become substantially injured, the same comprising a pipe 124 connected with the pipe 73 through the medium of a 25 T-coupling 125. This pipe 124 extends downwardly along one edge of the support 45 and is secured thereto by means of U-shaped clips 126, as shown. Connected with the lower end of the pipe 124 is a flexible 30 conduit or hose 127. As more clearly shown in Fig. 10, this hose is provided at its free end with metallic nipple 128, having screw-threaded engagement within the outer end of a blind port 129, extending longitudinally 35 through the lower end of the bar or element 52. It is thus seen that should the bar or element 52 break off the blind port 129 will be placed in communication with the atmosphere, whereby the pressure in the train line 40 will be reduced to apply the brakes and the train stopped.

The operation of the system is as follows:—

In accordance with the illustration in 45 Fig. 1, it is assumed that block D is occupied by a train, whereby the semaphore guarding block D is at danger or stop, the semaphore guarding block C at caution, and the semaphore guarding block B at clear. 50 Assuming that a locomotive or train is traveling in the direction of the arrows, from block A, into block B, then when the same moves in proximity to the ramps 29 and 30 near the entrance end of the block B, 55 the ramp-sections 29^a and 29^b engage with the contacts 57 and 58 carried by the shoe 56. The housing or casing 47 thus has its lower end swung outwardly and its upper end swung inwardly. Prior to this movement of the casing or housing 47, circuits are closed for energizing the magnets 88 and 89 whereby the rods or arms 82 and 83 are elevated, so that they clear the arms 50 and 51, when the latter are swung inwardly, 60 as above stated. As the block B is clear 65 there is a closed track circuit including the electro-magnet 26 of this block track circuit. In this closed track circuit current flows from one pole of the source of current 23 through wire 25, traffic rail 21 in block 70 A, wire 27, wire 28, traffic rail 20 in block A, and through wire 24 back to the opposite pole of the source of current. When the electro-magnet 26 is thus maintained energized, the armature 26', of the same is held 75 in engagement with a stationary contact 27', which is electrically connected with the contact blade 41. As the block B is clear, the semaphore paddle 32 assumes the uppermost position whereby the contact blade 41 is in 80 electrical engagement with the stationary contacts 37 and 38, whereby the ramp-sections 29, 30^a, and 29^b, 30^b, are electrically connected with one pole of the source of current 33. When the contact 57 engages the ramp-sections 29^a, as above stated, a circuit is closed 85 for energizing the electro-magnet 88. In this circuit current flows from one pole of the source of current 33 through armature 26', contact blade 41, contact 38, lead wire 90 36, ramp-section 29^a, contact 57, wire 57', electro-magnet 88, wire 88', the frame-work of the engine, and through the traffic rail 21 in the block back to the opposite pole of the source of current. It is thus seen that 95 the electro-magnet 88 will be energized and the arm 82 swung upwardly, whereby upon the inward movement of the arms 50 and 51, the valve structure 70 will not be operated to in turn operate the train stopping means. 100 When the contact 58 engages the ramp-sections 30^a, protecting the entrance end of the block B, as above stated, a circuit is closed to energize the electro-magnet 89, 105 whereby the same swings the arm or lever 105 83 upwardly, so that when the arm 51 is swung inwardly it clears the rod or arm 83, and the valve structure 71 will not be operated to operate the signal. In this closed 110 circuit current flows from one pole of the source of current 33, through armature 26', contact blade 41, contact 37, wire 35, ramp-section 30^a, contact 58, wire 58', electro-magnet 89, wire 89', the traffic rail 21 in block A, and back to the opposite pole of the source of current 33. Upon further longitudinal movement of the contacts 57 and 58 in engagement with ramps 29 and 30, the 115 above referred to circuits are open when they engage with the insulating material 20^c, of the ramps, such circuits being again closed when the contacts 57 and 58 engage with the ramp-sections 29^b and 30^b, which are 120 permanently connected with one pole of the source of current 33. When the contact 57 engages with the ramp-section 29^b, current flows from one pole of the source of current 33, through wire 34, ramp-section 29^b, contact 57, wire 57', electro-magnet 88, wire 88', the frame-work of the engine, and 125 130

through the traffic rail 21 in the block A back to the opposite pole of the source of current. When the contact 58 engages ramp-section 30^b, current flows from one 5 pole of the source of current 33, through wire 34, ramp-section 30^b, contact 58, wire 58' electro-magnet 89, wire 89', the frame-work of the engine and through the traffic rail 21 in block A back to the opposite pole 10 of the source of current 33. The engine is thus permitted to pass into the block B without the steam being cut off, the brakes applied, or the whistle sounded.

The engine now travels in block B toward 15 the entrance end of block C, and upon approaching the same the contacts 57 and 58 engage the ramp-sections 29^a and 30^a of the ramps which guard the entrance end of the block C. The lower end of the housing or 20 casing 47 is swung outwardly while the upper end thereof is swung inwardly, as is obvious. As block C is in caution condition the semaphore paddle 32 guarding the entrance end of the block C is in the intermediate 25 position, whereby the contact blade 41 electrically engages the stationary contact 39. As a result of this, ramp-section 29^a is in electrical connection with one pole of the source of current while the ramp-section 30^a 30 is disconnected therefrom (the contact blade 41 having now no electrical connection with the stationary contact 38). Upon the engagement of the contact 57 with the ramp-section 29^a, the circuit is closed for energizing 35 the electro-magnet 88, whereby the inward movement of the arm 50 will not actuate the valve 70 for stopping the train. In this closed circuit, current flows from one pole of the source of current 33 through arm 26', contact blade 41, contact 39, wire 40, wire 36, ramp-section 29^a, contact 57, wire 57', electro-magnet 88, wire 88', the frame-work of the engine, the traffic rail 21 in block B and back to the source of current 40 33. It is thus seen that the magnet 88 is energized whereby the train stopping means will not be actuated upon the inward movement of the arm 50. When the contact 58 engages the ramp-sections 30^a, the same be- 45 50 ing disconnected from the source of current 33, no circuit is closed for energizing the electro-magnet 89, the contact blade 41 having no electrical connection with the contact 37. It is thus seen when the arm 51 moves 55 inwardly, the same will strike the rod 83, and force the same inwardly for actuating the valve structure 71 of the signaling means. When this takes place the valve 78 of the valve structure 71 is unseated where- 60 65 by pressure enters the cylinder 72 through the pipe 73 and passes out through pipe 74', to the whistle 123, to sound the same. When the contacts 57 and 58 engage the ramp-sections 29^b and 30^b, circuits are closed for en- ergizing both electro-magnets 88 and 89 as

above explained. It is thus seen that the engine is permitted to pass into the entrance end of the block C, but the whistle 123 is operated to apprise the engineer of the caution condition of the block. The block 70 D being in danger condition, the semaphore paddle 32 protecting the entrance end thereof is in the lowermost position whereby the contact blade 41 has no electrical connection with either ramp-section 29^a or 30^a, these 75 ramp-sections being further disconnected with the source of current at 27' since the electro-magnet is de-energized, due to a train in the block D. When the contacts 57 and 58 engage ramp-sections 29^a and 30^a no circuits are closed for energizing the electro-magnets 88 and 89, whereby upon the inward movement of the arms 50 and 51 they will 80 engage the rods or arms 82 and 83, and actuate the valve structures 70 and 71 respectively. Upon the operation of the valve structure 70 the valve 78 thereof is unseated, whereby pressure enters the cylinder 70 and passes out of the same through pipe 74. The 85 pressure is carried by pipe 74 into the inlet end of the cylinder 95, forcing the piston 96 thereof forwardly. This movement of the piston unlatches the throttle lever 105 and moves the same to its closed position for cutting off the steam. The pressure within the 90 pipe 74 also passes through the pipe 91, into the cylinder 92, to move the piston therein, which through the medium of the rod 93 moves the engineer's brake valve 94 to the active position to reduce the pressure 95 in the train line and applies the brakes. The 100 brakes are applied a little in advance of the cutting off of the motive power as above explained. The valve structure 71 being simultaneously operated with the valve structure 70 the whistle 123 is operated as above 105 explained. When the contacts 51 and 58 engage the ramp-sections 29^b and 30^b electro-magnets 88 and 89 are energized as hereinabove explained. It is thus seen when the 110 engine traveling in block C approaches the entrance end of block D, which is in danger condition, such engine is automatically stopped and the signal is sounded.

The function in providing the ramp-sections 29^b and 30^b connected therewith and insulated from the ramp-sections 29^a and 30^a respectively in end to end relation, is to provide means whereby the train stopping means and the signaling means will not be 115 operated when the engine is driven in an opposite direction to the direction of the traffic on the track. This is important as it is often necessary in the operation of railroads to back the train or engine for a short 120 distance, and it is disadvantageous to have the safety means operate under these conditions.

Upon the engine passing each ramp, the operative indicating signal 123' is operated, 130

as rod or arm 79 of valve structure 71' is permanently in the path of travel of the head 49, thus apprising the engineer of the passing of the ramp and the operative condition of the system.

It will be readily understood that oppositely disposed ramps may be provided as described on both sides of the track to protect a train in moving either forward or back, in which case the locomotive, car or the like is provided with similar mechanism on both sides for operating the train stopping and signal operating means in the cab, and such duplication is contemplated as 15 within the present invention.

It is also to be understood that the present invention contemplates the use thereof in connection with either automatic block signal systems or mechanically operated signals, the present system being operative as 20 described however the semaphore paddles are operated.

It is also to be understood that the batteries employed in connection with automatic block signal systems may be employed if desired to furnish current for operating the present system, such use not interfering with the operation of the automatic signal 25 systems.

30 It is also to be understood that independent ramps may be located at any desired points along the right of way, as for example, to protect against an open drawbridge, an open switch or the like, in which case a separate battery is used to supply current continuously to the ramps, means being provided to open the circuit between the ramp and battery when the draw or switch is opened.

40 It is to be further understood that the form of my invention herewith shown and described is to be taken as a preferred example of the same, and that various changes in the shape, size and arrangement of parts 45 may be resorted to without departing from the spirit of the invention or the scope of the subjoined claims.

Having described my invention, I claim,

1. Apparatus of the character described, 50 comprising a pivoted member to be suitably mounted upon a vehicle, an element carried by the pivoted member and movable longitudinally thereof and provided with a contact, a ramp arranged in the path of travel 55 of the contact and adapted when engaging the same to swing the element and member in one direction, means for actuating train stopping means embodying a member adapted when in one position to be engaged by the 60 first named member upon the movement thereof in one direction, and an electrical device adapted when energized to shift the second named member so that it will not be engaged by the first named member upon 65 the said movement thereof.

2. Apparatus of the character described, comprising a plurality of members having 70 slidable engagement to move longitudinally with relation to each other and to swing laterally together, means pivotally connecting them with a vehicle, train stopping means adapted to be operated by a swinging movement of said members in one direction under certain conditions, electrically operated means for controlling the operation of 75 the train stopping means by the movement of said members, and mechanical means to swing the members in one direction.

3. Apparatus of the character described, comprising a plurality of members having 80 slidable engagement to move longitudinally with relation to each other and to swing laterally together, means pivotally connecting one member with a vehicle, signaling means adapted to be operated by a swinging movement of said members in one direction under certain conditions, electrically operated means for controlling the operation of the 85 signaling means by the movement of said members, and a ramp arranged in the path 90 of travel of one of the members for engagement therewith to swing the same laterally in one direction.

4. Apparatus of the character described, comprising a substantially vertically arranged tubular casing, means pivotally connecting the same with a vehicle, an element 95 mounted to reciprocate within the tubular casing, train control means arranged near the upper end of the tubular casing and 100 adapted to be actuated by the same upon the swinging movement thereof under certain conditions, electrically operated means adapted when energized to prevent the operation of the train control means by the 105 movement of the tubular casing, and a ramp disposed in the path of travel of the element for engagement therewith to swing the same in one direction.

5. Apparatus of the character described, 110 comprising a substantially vertically arranged tubular casing, means to pivotally connect the same with a vehicle whereby it may be swung transversely thereof, spring 115 means to normally retain the tubular casing in a substantially vertical position, an element mounted to reciprocate within the tubular casing and depending therefrom and provided with contact means, train control means arranged near the upper end of the 120 tubular casing and adapted to be operated upon the movement thereof in one direction under certain conditions, electrically operated means adapted when energized to prevent the train control means being operated 125 by the movement of the tubular casing, electrical connections between the contact means and the electrically operated means, a ramp disposed in the path of travel of the contact means for engagement therewith to swing 130

the reciprocating element laterally in one direction, a source of current, and means for connecting and disconnecting the source of current with and from the ramp.

5 6. Apparatus of the character described, comprising fluid pressure operated train stopping means, a valve to control the operation of the same, a pivoted member adapted to operate the valve under certain conditions, electrically operated means for controlling the operation of the valve by the pivoted member, means to move the pivoted member including an element connected therewith and freely movable longitudinally 10 thereof, and mechanical means to move the element laterally.

7. In a train control system, a track divided by insulating means into blocks, a plurality of ramps for guarding the entrance end of each block, each ramp being formed of a plurality of insulated ramp sections correspondingly arranged with relation to the ramp sections of the other ramp, a source of current, means permanently connecting corresponding ramp sections of the ramps with the source of current, and means connecting and disconnecting the other corresponding ramp sections of the ramps with and from the source of current.

8. In a train control system, a track divided by insulating means into blocks, a plurality of ramps for guarding the entrance end of each block and arranged in superposed relation, each ramp being formed in 35 a plurality of insulated ramp sections, a source of current, means connecting one ramp section of each ramp with the source of current, and means connecting and disconnecting the other ramp section with and 40 from the source of current.

9. Apparatus of the character described, comprising a track, a ramp arranged near the track, a vehicle to travel on the track, a

movable mechanically operated structure connected with the vehicle, signaling means 45 permanently adapted to be operated by the movement of the structure in one direction, a second signaling means adapted to be operated by a corresponding movement of the structure under certain track conditions, 50 train stopping means adapted to be operated by a corresponding movement of the structure under certain track conditions, and electrically operated means adapted when energized for rendering the second signaling 55 means and the train stopping means inoperative, substantially as described.

10. In apparatus of the character described, a track, a ramp arranged near the track, a vehicle to travel upon the track, an 60 apertured support secured to the vehicle, a member pivotally connected with the support and adapted to engage with the ramp to be moved thereby, rods mounted to reciprocate within the apertures of the support 65 and engaging with the member near its ends, springs surrounding the rods to oppose the swinging movement of the member, and train control means adapted to be operated by the movement of the member in one direction. 70

11. In apparatus of the character described, a member adapted to be mechanically operated having a recess formed therein, a sleeve formed of insulating material 75 and mounted to reciprocate within the recess, a contact element carried by the sleeve, and a spring extending into the sleeve to oppose its movement in one direction.

In testimony whereof I affix my signature 80 in presence of two witnesses.

WILLIAM BROOKS MURRAY.
